Primary Examiner — George J Ulsh*Assistant Examiner* — Bethany Louise Mallino(74) *Attorney, Agent, or Firm* — Hemisphere Law, PLLC;
 Zhigang Ma(57) **CLAIM**

The ornamental design for a vacuum cleaner storage rack as shown and described.

DESCRIPTION

FIG. 1 is a front, right, and top perspective view of the vacuum cleaner storage rack, showing my new design; FIG. 2 is a rear, left, and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof. The broken lines depict portions of the vacuum cleaner storage rack that form no part of the claimed design.
